CLAIM

The ornamental design for a carrier for cans or the like, as shown and described.

DESCRIPTION

FIG. 1 is an isometric view of a carrier for cans or the like showing our new design;

FIG. 2 is a top plan view of the carrier turned 90 degrees from the position in FIG. 1;

FIG. 3 is a front elevational view thereof;

FIG. 4 is a rear elevational view thereof; and

FIG. 5 is a side elevational view thereof.

FIG. 1

FIG. 2

FIG. 3

FIG. 5

FIG. 4
